UNITED STATES PATENT OFFICE

98,209

DESIGN FOR A SHEET METAL SNAP FASTENER CAP

Edwin S. Blanchard, Cambridge, Mass.

Application November 27, 1934, Serial No. 54,178

Term of patent 7 years

To all whom it may concern:

Be it known that I, Edwin S. Blanchard, a citizen of the United States and a resident of Cambridge, in the county of Middlesex and State of Massachusetts, have invented a new, original, and ornamental Design for a Sheet Metal Snap Fastener Cap, of which the following is a specification, reference being had to the accompanying drawing, forming a part thereof in which:

Figure 1 is a plan view of a sheet metal snap fastener cap showing my new design;

Fig. 2 is an edge view of the cap shown in Figure 1; and

Fig. 3 is a sectional view taken on the line 3—3 of Figure 1.

I claim:

The ornamental design for a sheet metal snap fastener cap as shown.

In testimony whereof, I have signed my name to this specification.

EDWIN S. BLANCHARD.
